UNITED STATES PATENT OFFICE.

THOMAS P. HAGEMAN, OF ST. LOUIS, MISSOURI.

CONDENSER.

Application filed September 14, 1925. Serial No. 56,125.

This invention relates to condensers, and an object thereof is to provide a condenser in which compressed gas is forced from a compressor into the condenser and subjected to the action of air forced through condenser tubes of novel construction, whereby the gas is cooled and condensed to liquid more efficiently and rapidly than by the use of condensers of different construction.

Another object of the invention is to provide a condenser embodying the novel construction and obtaining the advantages of the condenser herein disclosed.

Other objects will appear from the following description, reference being made to the accompanying drawing in which

Fig. 1 is an end elevation of a machine consisting of a compressor and the present condenser.

Fig. 2 is a view showing the condenser in section.

Fig. 3 is a view showing gearing for operating the fan by which cooling air is drawn through the condenser tubes.

Fig. 4 is an enlarged vertical sectional view of the condenser similar to Fig. 2.

Fig. 5 is a cross sectional view on the line 5—5 of Fig. 4.

Fig. 6 is an elevation of one of the condenser tubes.

The invention is shown in connection with a compressor 1 from which a pipe 2 conducts the compressed gas into a condenser casing 3 above the level of the liquid produced in the condenser casing as a result of cooling and condensing the gas. From the condenser the liquid passes through a pipe 4 to the coils, not shown, or other place of use, and thence is returned through a larger pipe 5 shown as surrounding the pipe 4 but not in communication with the condenser. From the pipe 5 the gas is conducted through a pipe 6 to the compressor and thence through the pipe 2 to the condenser for repeated use.

The tubes 7 of the condenser are of novel construction, being of serpentine or crooked formation as will be understood by reference to Fig. 6, with a circumferential flange or fin 8 at each bend. In this way the cool air is prevented from passing in a straight line through the condenser tubes and all of the air is caused to contact with the walls of the condenser tubes at some point or another. The tubes and the flanges or fins 8 are thus cooled and the gas delivered to the con-

denser from the compressor is condensed to liquid.

The lower ends of the condenser tubes 7 open through the bottom wall 9 of the condenser, and the upper ends of the tubes open 60 through the top wall 10 of the condenser. Air is admitted to the condenser through an air inlet pipe 11 (Fig. 2) opening into a drum or chamber 12 into which the lower ends of the condenser tubes open and from 65 which the air passes through the condenser tubes to a chamber 13 above the condenser. From the chamber 13 the air passes through an opening 14 to an outlet pipe 15.

The speed of circulation and the passage 70 of air through the condenser is increased by an air propeller or fan device adjacent to the outlet opening 14 and consisting of a number of blades 16 supported between arms 17 attached to a rotary shaft 18. The shaft 18 extends through the condenser through a straight tube 19 and at its lower end has a pinion 20 (Fig. 3) meshing with a pinion 21 on a shaft 22 driven by gearing 23 from a shaft 24 operated by the motor 25 of the 80 compressor.

From the foregoing the advantages obtained by use of my improved condenser are obvious as is the fact that the invention obtains all of its intended objects and purposes in a very efficient manner. The condenser may be constructed at comparatively low cost and assembled and used without difficulty. I do not restrict myself in unessential particulars, but what I claim and desire to secure by Letters Patent is:—

1. A condenser comprising a casing having upper and lower end walls each provided with a series of holes, a series of sinuous tubes in said casing having their respective 95 ends opening through said holes in said upper and lower end walls, a chamber below said casing into which the lower ends of all of said tubes open, a chamber above said upper end wall into which the upper ends 100 of all of said tubes open and provided with a central outlet opening through the center thereof, a pipe into which said outlet opening opens, a vertical tube in said casing opening through said upper and lower end walls, a shaft extending through said vertical tube and through said upper chamber into said pipe, mechanism extending into said lower chamber for rotating said shaft, and a propeller device attached to said shaft in said 110

outlet pipe adjacent to said outlet opening from said upper chamber.

2. A condenser comprising a casing having upper and lower end walls each provided with a series of holes, a series of sinuous tubes in said casing having their respective ends opening through said holes in said upper and lower end walls, a chamber below said casing into which the lower ends of all of said tubes open, a chamber above said upper end wall into which the upper ends of all of said tubes open and provided with a central outlet opening through the center thereof, a pipe into which said outlet open-

ing opens, a vertical tube in said casing 15 opening through said upper and lower end walls, a shaft extending through said vertical tube and through said upper chamber into said pipe, mechanism extending into said lower chamber for rotating said shaft, a propeller device attached to said shaft in said outlet pipe adjacent to said outlet opening from said upper chamber, an inlet pipe opening into said casing and an outlet pipe opening from said casing below the plane of said 25 inlet pipe.

THOMAS P. HAGERMAN.
